UNITED STATES PATENT OFFICE.

REXFORD M. SMITH, OF WASHINGTON, DISTRICT OF COLUMBIA, ASSIGNOR, BY MESNE ASSIGNMENTS, TO CONNECTICUT AIRCRAFT COMPANY, OF NEW HAVEN, CONNECTICUT, A CORPORATION.

FLYING-MACHINE.

1,118,881.

Specification of Letters Patent. Patented Nov. 24, 1914.

Application filed February 13, 1909. Serial No. 477,677.

To all whom it may concern:

Be it known that I, REXFORD M. SMITH, a citizen of the United States, residing at Washington, in the District of Columbia, 5 have invented a certain new and useful Flying-Machine, of which the following is a specification, reference being had therein to the accompanying drawing.

This invention relates to flying machines 10 of the aeroplane or heavier than air type, the object of the invention being to provide a machine of the class described in which provision is made in a practical and reliable manner for maintaining the poise or 15 balance or equilibrium of the machine both while moving in the normal direction of travel and while descending after stopping the motor and propelling mechanism, thus rendering it safe to descend at any time in 20 case of accident to the motor or any part of the propelling mechanism resulting in the stoppage of the propeller of the machine.

A further object of the invention is to 25 provide a novel form of aeroplane embodying a plurality of lifting surfaces. Such plane may be all in one or embody a plurality of sections each embodying a lifting surface and arranged one in advance of another.

30 A further object of the invention is to so arrange the aeroplane sections as to provide for a reliable poise of the machine both while moving and at rest; also to combine with the lifting plane or planes, one or more 35 poising planes which perform their function when the forward progress of the machine is arrested, as by the stoppage of the propeller from any cause.

A further object of the invention is to 40 provide one or more lateral balancing and steering planes or rudders which occupy a normally horizontal position but which are adapted to be tilted to offer the necessary resistance to cause the machine to describe an 45 arc, whereby the direction of movement of the machine may be controlled.

A further object of the invention is to 50 provide in connection with the steering planes or rudders, and the ascending and descending plane or planes, a single controlling element by means of which the aviator may cause the machine to rise or descend or turn either to the right or to the left.

With the above and other objects in view 55 the nature of which will more fully appear

as the description proceeds, the invention consists in the novel construction, combination and arrangement of parts herein fully described, illustrated and claimed.

In the accompanying drawings: Figure 1 60 is a plan view of a flying machine embodying the present invention. Fig. 2 is a vertical longitudinal section through the same. Fig. 3 is a vertical cross section thereof taken just in rear of the ascending and descending planes. Figs. 4 to 14 both inclusive, are diagrams illustrating side edge views of various forms of lifting planes embodying a plurality of lifting surfaces. Fig. 15 is an enlarged detail view partly in section of the control. 70

In the preferred embodiment of the invention, the machine comprises in connection with a suitable frame work, upper and lower aeroplanes or as they may be 75 termed lifting planes as their principal function is to provide the necessary resistance to effect a lifting of the machine as it is propelled through the air. These upper and lower aeroplanes are best shown in Figs. 80 2 and 3 and in the preferred embodiment of the invention, the upper lifting plane and the lower lifting plane are both made up of sections, the upper plane comprising fore and aft sections 1 and 2 respectively, and 85 the lower plane embodying corresponding fore and aft sections 3 and 4 respectively.

As shown in Fig. 2, the forward section of each plane has its forward portion upwardly deflected as shown at 5, the remainder of 90 the plane being substantially flat and horizontally disposed when the machine is in motion. The rear plane has its rear portion downwardly deflected as shown at 6 while the remaining portion of the plane is substantially flat and horizontally disposed. The upwardly deflected forward portion 5 and the downwardly deflected portion 6 constitute lifting surfaces the current of air 95 striking against the undersides of the aeroplane sections offering the necessary resistance in connection with the lifting surfaces 5 and 6 to correspondingly and simultaneously move the said aeroplane sections upward or give the same an upward tendency 100 in accordance with the speed at which the machine is propelled. It is also preferred to slant or pitch the opposite wing portions 105 of the aeroplane sections from the center of the machine upward toward their outer 110

extremities as shown in Fig. 3 as such arrangement is of assistance in maintaining the horizontal poise and the equilibrium of the machine as a whole.

- 5 Instead of making each aeroplane to consist of fore and aft sections as shown in Fig. 2, both of such sections may be combined in one as illustrated in Fig. 4, 7 designating such a plane which has at its forward end an 10 upwardly deflected lifting portion 8 and at its rear end a downwardly deflected lifting portion 9. The plane may also be divided into fore and aft sections as shown in Fig. 5, each section 10 of which embodies an upwardly deflected forward lifting portion 11 and a downwardly deflected lifting portion 12. Instead of deflecting the rear portions of the sections downward as shown in Fig. 5, such rear portions may also be deflected 15 upward as shown at 13 in Fig. 6, the forward portions 14 being deflected upwardly to form lifting surfaces and the intermediate or body portions 15 of the sections being substantially flat.
- 20 Instead of two sections as shown in Fig. 6, three of such sections may be employed as shown in Fig. 7. Three or more sections 10 similar to the sections shown in Fig. 5 may be employed as shown in Fig. 8 and 25 these sections may be united or joined together by a top flat connecting plane 16 or by frame bars in place of the plane 16. Instead of connecting the planes 10 in the manner shown in Fig. 8, said planes may be provided with overlapping extensions 17 as 30 shown in Fig. 9. Carrying out the idea of providing each aeroplane or aeroplane sections with front and rear lifting surfaces, the same may be constructed as indicated in 35 Fig. 10 wherein I have shown an aeroplane section 18 having a forward lifting surface 19 curved from the extreme front edge of the main body of the plane downward and a rear lifting surface 20 formed by deflecting the rear edge of the plane downward. 40 Instead of extending the front lifting surface downward from the body of the plane as shown in Fig. 10, said forward lifting surface may be extended upward from the body of the plane as shown at 21 in Fig. 11. The rear lifting surface of the aeroplane section may also be detached or disconnected 45 from the main body 22 of the plane as shown in Fig. 12 and disposed as shown at 23. Or 50 said rear lifting surface of the plane may be attached at its forward edge to the body of the plane 22 as shown at 24. It is also contemplated to hinge the rear lifting surface or portion of the plane 22 to the rear edge 55 of the main body of the plane as indicated in Fig. 14 and to provide means for normally holding the said rear lifting portion in the lifting position shown in Fig. 14 while permitting the said portion 23 to be released 60 by a suitable device so that it may move

upward to a limited extent until it occupies the dotted line position shown in Fig. 14 when the plane as a whole will assume the same form as illustrated in Figs. 6 and 7.

It will thus be seen that in all of the forms of the lifting plane, or lifting plane sections, provision is made for obtaining a double lift or in other words a lifting surface is provided at the front and also at the back thus causing each plane or plane section to maintain its own poise or equilibrium. This effect is greatly enhanced by arranging the aeroplane sections at a suitable distance in advance of one another so as to leave an intervening space or spaces which will permit the air after acting upon the lifting surfaces of the plane sections to escape upward and allow the succeeding current to act with equal effect upon the lifting surfaces.

Where the aeroplane sections are arranged with an intervening space between them as shown in Fig. 2 for example, poising planes 25 may be placed between the lifting plane sections as shown in Figs. 2 and 3 and the opposite wing portions of the poising plane will be slanted upward and outward to a greater degree than the lifting plane thereby adding greatly to the capability of the machine for automatically maintaining its equilibrium in the air. The poising plane or planes 25 are used principally for balancing the machine when the power is cut off so as to cause the machine to float to the earth without careening or listing to any material or dangerous extent. The said poising planes are disposed edgewise horizontally so that in the forward movement of the machine, they will offer no resistance, the function of said planes being brought into play only when descending.

The frame of the machine is shown as comprising runners 26 which form a rest for the machine while in contact with the ground. To the upturned forward extremities of the runners are connected the ascending and descending planes and while one of such planes may suffice, I have illustrated a pair of planes, the upper ascending and descending plane being indicated at 27 and the lower plane being indicated at 28. These planes will ordinarily be pivotally connected at 29 to the extensions of the frame or runners and one of the frames will be provided with a lever arm 30 to which is pivotally connected the forward extremity of a connecting rod 31, the rear extremity of which is pivotally connected at 32 to a lug on a sleeve or loose collar 33 within which the steering post 34 of the control is adapted to turn, the collar or sleeve 33 being confined between fixed collars or shoulders 35 on the steering post. The post is shown as provided at its upper end with a hand wheel 36 while the lower end of the post is journaled in a bearing 37.

step 37 pivoted on a horizontal axis to the frame as indicated at 38 to enable the wheel 36 to be moved forward or backward in order to correspondingly move the connecting rod 5 31 and thereby tilt the planes 27 and 28, the said planes being connected for simultaneous movement by means of pivotal stanchions or bars 39.

Mounted fast upon the steering post 34 10 is a drum or pulley 40 adapted to receive and operate steering connections 41 which lead off in opposite directions to the lever arms 42 of the steering planes or rudders 43. These rudders or steering planes, as shown 15 in Fig. 1, are normally disposed horizontally and edgewise to the air current and between the fore and aft aeroplane or lifting plane sections. They are also located by preference at the extreme outer edges of the aero- 20 plane as a whole and are adapted to turn on an axis which lies in front of the center of the planes thereby rendering the planes self-balancing so that in the forward movement of the machine the action of the air current 25 thereon will preserve the horizontality of the planes. Either one of said planes may however, be tilted to form a resisting medium and this will act as a hold back for one side or the other of the machine, the resistance of 30 the air against the tilted steering plane or rudder being thus utilized to cause the machine to turn to the right or left in accordance with the steering plane or rudder which is so tilted, it being understood that by tilt- 35 ing one of the steering planes and not disturbing the other steering plane, the tilted plane will offer a resistance to the forward movement of that side of the machine, thereby holding back such side and allowing the other side to move forward with greater 40 rapidity, thereby effecting a turning or steering of the machine as a whole. In turning the post 34, one of the connections 41 is pulled and the other slackened, thus deflecting 45 one steering plane without affecting the other.

I prefer to locate the motor 44 well down and preferably under the deck 45 of the machine and transmit motion to the propeller shaft 46 by a chain 47 or its equivalent extending from the motor shaft to the propeller shaft. I also prefer to use a single propeller 48 directly on the end of the propeller shaft and centrally of the back of 50 the machine. By means of the control above described it will be understood that the aviator, by means of a single controlling element, may operate both the ascending and descending planes and the steering or rudder planes. The connections 41 are preferably 55 so arranged that by turning the wheel 36 to the right, the machine will turn in the corresponding direction and by turning the wheel to the left, the machine will be directed to the 60 left. By carrying the wheel 36 forward, the

plane or planes 27 and 28 will be tilted so as to cause the machine to ascend and by moving the wheel 36 backward, said plane or planes will be reversely tilted so as to cause the machine to descend.

70

I claim:

1. In a flying machine, an aeroplane comprising fore-and-aft sections, the body portions and adjacent edges of which are in substantially the same horizontal plane, one section having an upwardly deflected lifting surface lying wholly above the body portion of said section and the other section having a downwardly deflected lifting surface lying wholly below the body portion 75 of said section.

2. In a flying machine, an aeroplane comprising a body portion having its lead and trail edges bent or deflected respectively upwardly and downwardly at an acute angle 80 to and above and below the plane of said body portion, the body portion being of materially greater fore-and-aft dimensions than the said bent or deflected edges thereof.

3. In a flying machine, fore and aft sus- 90 taining planes each having a dihedral angle, and an intermediate poising plane inclined to the plane of the sustaining planes.

4. In a flying machine, fore and aft sus- 95 taining planes each having a dihedral angle, and a fixed intermediate poising plane having a dihedral angle of greater pitch than the sustaining planes.

5. In a flying machine, sustaining sur- 100 faces arranged one in rear of the other and spaced to provide an intervening gap, stabilizing planes arranged at the extremities of the gap between said sustaining surfaces, and means for controlling said stabilizing planes.

6. In a flying machine, sustaining sur- 105 faces arranged one in rear of the other and spaced to provide an intervening gap, vertically movable stabilizing planes mounted at the extremities of the gap to swing on horizontal axes, and means for swinging 110 said planes.

7. In a flying machine, a supporting sur- 115 face comprising a sustaining plane having dihedrally inclined wings, and a poising plane having wings normally arranged out of horizontal and vertical alinement with the wings of the sustaining plane and inclined at a greater dihedral angle.

8. In a flying machine, a supporting sur- 120 face comprising a sustaining plane, and a poising plane, said poising plane embodying wings offset vertically and horizontally from the wings of the sustaining plane and normally inclined at a fixed angle thereto.

9. In a flying machine, a supporting sur- 125 face comprising a sustaining plane and a poising plane, said planes being arranged out of horizontal and vertical alinement, the sustaining plane having its wings set at a 130

slight dihedral angle and the poising plane having its wings normally set at a greater dihedral angle.

10. In a flying machine, an aeroplane comprising a body portion having an upturned front edge and a downturned rear edge, said body portion being of materially greater fore-and-aft dimensions than said edges, each of said edges being bent substantially at an oblique angle to the body portion, the latter being arranged to lie on a

line intermediately between and parallel with horizontal planes passing through the extreme free edges of the said upturned front portion and downturned portion. 15

In testimony whereof I affix my signature in presence of two witnesses.

REXFORD M. SMITH.
